APPARATUS FOR DEODORIZING VEGETABLE OILS

Joseph Stewart, Elmhurst, N. Y.

Application March 12, 1938, Serial No. 195,449
In Great Britain October 7, 1936

2 Claims. (Cl. 87—12)

This invention relates to apparatus for deodorizing vegetable oils such, for example, as cocoanut oil, palm oil, cotton seed oil and linseed oil.

The invention has for its purpose to provide efficient and economical means for effecting deodorization of vegetable oils by heat and steam treatment of the oil to be deodorized.

The accompanying drawing illustrates a preferred embodiment of the invention in a duplex deodorizing apparatus or plant, the apparatus being shown partly in vertical section.

Referring to the drawing by reference characters, 1 designates an oil supply tank for vegetable oil to be treated, 2 designates generally a surface type oil heating device, and 3 and 3^a designate final deodorizing tanks or vessels. Extending downward from the bottom of supply tank 1 is an outlet pipe 4 and extending downward from the bottoms of the deodorizing vessels 3 and 3^a respectively are pipes 5 and 5^a. Pipes 6 and 6^a are connected with pipe 4 through a three-way valve 7 and are connected with pipes 5 and 5^a and pipes 9 and 9^a through three-way valves 8 and 8^a. Three-way valves 10 and 10^a connect pipes 5 and 5^a respectively with horizontal pipes 11 and 11^a which lead from pipes 5 and 5^a above valves 8 and 8^a into the lower ends of upstanding pipes 12 and 12^a.

Pipes 12 and 12^a extend up above the tops of vessels 3 and 3^a and have horizontal extensions 13 and 13^a extending into the upper part of a casing 14 of the heater 2 to an oil discharge pipe 15 having lateral branches 15^a with downturned ends. Three-way valves 16 and 16^a connect with pipes 12 and 12^a, respectively, pipes 17 and 17^a which extend and discharge into the upper part of vessel 3 and the upper part of vessel 3^a. Pipes 12 and 12^a are closed at their bottoms or lower ends by suitable heads or plugs 18 and 18^a through which extend jet devices or nozzles 19 and 19^a for discharging jets of superheated steam upward into the lower ends of pipes 12 and 12^a. Nozzles or steam jets 19 and 19^a are connected by pipes 20 and 20^a to a source of superheated steam (not shown), and shut-off valves 21 and 21^a are provided for opening and shutting off the steam supply to the nozzles.

50 A pipe 22 opens into pipe 12 between jet or nozzle 19 and valve 16, and a pipe 22^a opens into pipe 12^a between jet or nozzle 19^a and valve 16^a. Pipes 9 and 22 and a discharge pipe 23 for deodorized oil are connected by a three-way valve 24, and pipes 9^a and 22^a and a discharge pipe 23^a for deodorized oil are connected by a three-way valve 24^a. Interposed in pipe 9 intermediate valves 8 and 24 to pump oil through pipe 9 from valve 8 to valve 24 is a suitable rotary pump 25, and interposed in pipe 9^a intermediate

5 ate valves 8^a and 24^a to pump oil through pipe 9^a from valve 8^a to valve 24^a is a suitable rotary pump 25^a.

Adjacent the bottom of and within the vessels 3 and 3^a respectively are perforated steam pipes 26 and 26^a of known construction for discharging steam downward into the respective vessels. In the apparatus shown, the perforated discharge pipes 26 and 26^a respectively are connected by pipes 27 and 27^a to a source of saturated steam (not shown). Suitable shut-off valves 28 and 28^a are provided in pipes 27 and 27^a respectively, for permitting steam to be supplied to and cut-off from the perforated discharge pipes at will.

15 A suitable vacuum pump and suitable vapor condenser (not shown) are connected to a suction outlet 29 located at the top of the heater casing 14, and are also connected to suction outlets 30 and 30^a located at the tops of vessels 20 3 and 3^a respectively. Water vapor, steam, and all volatile products released in casing 14 and vessels 3 and 3^a in treating oil will be sucked out through these outlets.

The oil heating device generally designated by the reference character 2, comprises the casing 14 having an oil discharge pipe 31 leading from the bottom of the casing, and heating means of the surface type within said casing. The heating means comprises a horizontally disposed oil-receiving and discharging trough 32 which is arranged in the upper part of casing 14 to receive oil from branches 15^a of pipe 15 and has in and along its bottom a narrow oil discharge slot 33 having serrated longitudinal edges. Directly under the slot is a unit for splitting or dividing the wide thin sheet or film of oil descending from the long narrow slot into two very thin descending halves and heating the adjacent or innermost faces of the two halves 40 or divisions of said sheet of oil as they descend toward the bottom of casing 14. This unit is arranged between the trough and the bottom of the casing. It comprises a vertical bank or series of superposed horizontal pipes 34, each 45 two immediately superposed ones of which pipes are connected by one of a series of vertical plates 35, the plates 35 and the axes of the pipes 34 lying in the same vertical plane as the slot 33 in trough 32. The pipes 34 are connected by 50 return bends 36 for flow of a suitable heating medium such as hot gas through the pipes of the series from the lowermost one to the uppermost one of said pipes, the lowermost pipe extending out through a vertical end wall of casing 14 for connection to a suitable source of supply (not shown) of said heating medium, and the uppermost pipe extending out through a vertical end wall of casing 14 for connection to a suitable outlet or exhaust (not shown) 55 60

for the heating medium. Said lower and upper pipes extend through suitable stuffing boxes 37 and 38 held to the casing 14.

A three-way valve 39 connects the lower end 5 of the oil discharge pipe 31 of the heating device to pipes 40 and 40^a which extend and discharge into the upper part of vessels 3 and 3^a.

A back-pressure check valve 41 is provided in pipe extension 13 and a back-pressure check 10 valve 41^a is provided in pipe extension 13^a, both said valves opening toward the heating device 2 as indicated in the drawing. A back-pressure check valve 42 is provided in pipe 40 and a back-pressure check valve 42^a is provided in pipe 40^a, 15 valve 42 opening toward vessel 3, and valve 42^a opening toward vessel 3^a, as indicated in the drawing.

The invention provides an apparatus whereby a body of oil withdrawn from a tank 1 may be 20 first charged into one of the final deodorizing tanks or vessels 3 or 3^a to partially fill said vessel as shown, the charging then stopped, the oil in the vessel then circulated from and back to the vessel via the heating device and then without passing through the heating device, and the deodorized oil may finally be discharged from 25 said vessel, provides means whereby, during circulation of the oil from and back to the deodorizing vessel, the oil may be completely deodorized 30 by steam treatment, and provides means whereby, during completion of deodorization of oil in one of said vessels, a body of oil from tank 1 may be charged into the other vessel, and treatment thereof by heat and steam for deodorization 35 in and discharge from said other vessel may be started. Deodorizing treatment of two bodies of oil may thus be carried on with the deodorizing processes for the two batches of oil at different stages. Great economy in plant cost, 40 plant space and plant operation are thus made possible. The apparatus also provides for more efficient deodorization of the oil, for completion of deodorization in a minimum of time, and for complete deodorization of a body of oil by the 45 use of a single oil vessel to which oil from a heater is supplied for full deodorization.

The following description will make clear to those skilled in the art the operation and advantages of the apparatus. To treat oil in vessel 50 3, valve 7 is set to cut off pipe 6^a from pipes 4 and 6 and connect pipes 4 and 6. Valve 8 is set to connect pipes 6 and 5 and cut off pipe 9. Valve 10 is set to connect pipe 11 to pipe 5 and cut off vessel 3 from pipe 5. Valve 24 is set to cut 55 off pipe 22 from pipes 9 and 23. Valve 16 is set to cut off the heater 2 and the upper section of pipe 12 from the lower section of said pipe 12 and connect pipe 17 to the lower section of said pipe 12. Valve 21 is then opened to start a jet 60 of superheated steam upward in the lower section of pipe 12, whereupon oil from tank 1 will pass through pipe 4, valve 7, pipe 6, valve 8, pipe 5, valve 10, pipe 11, lower section of pipe 12, valve 16 and pipe 17 into vessel 3.

When vessel 3 has been partly filled with oil the supply is cut off and the vessel 3 is put in circulatory connection with heater 2. This 65 may be done by simply setting valve 10 to cut off flow from pipe 6 via pipe 5 and valve 10 to pipe 11 and open tank 3 via pipe 5 and valve 10 to pipe 11, by setting valve 16 to cut off pipe 17 from pipe 12 and to permit oil to flow from the lower section to the upper section of pipe 12 through pipe 16, and by setting valve 39 to open pipe 40 to pipe 31 and cut off pipe 40^a from

pipe 31. Valve 7 may also be set to cut off pipe 6 from pipe 4, and valve 8 may be set to cut off pipe 6 from pipes 5 and 9. From the body of oil previously charged into vessel 3, oil will now be circulated continuously, as a result of 5 the action of the steam jet discharging into pipe 12 from nozzle 19, via the following circuit: vessel 3, pipe 5, valve 10, pipe 11, pipe 12, pipe extension 13, pipe 15 and its branches 15^a, heating device 2, pipe 31, valve 39 and pipe 40 back 10 to vessel 3. This circulation of the vegetable oil is maintained until a desired final deodorizing temperature of the oil in vessel 3 is attained, this temperature (as is well known) being generally in the range of 450 to 500 degrees Fahrenheit. 15

From this point the deodorization of the oil charged into vessel 3 is completed without further use of the heating device 2. The completion of the deodorizing treatment of the oil in 20 vessel 3 is effected by setting valve 39 to cut off pipe 31 from pipe 40, and by setting valve 16 to cut off the upper section of pipe 12 from the lower section of pipe 12 and to open the lower section of pipe 12 to pipe 17. The jet of superheated steam from nozzle 19 will now circulate the oil in vessel 3 via pipe 5, valve 10, pipe 11, lower section of pipe 12, valve 16, and pipe 17 back into vessel 3. While this last mentioned circulatory steam treatment of the oil may be 25 used alone to complete the deodorization of the oil, it is preferred (for best results) to first so treat the oil with superheated steam and to thereafter shut-off the steam jet 19 by means of a valve 21 and to treat the oil in vessel 3 30 for a time with saturated steam discharged into the lower part of the body of oil in vessel 3 through the perforated pipe 26. This may be 35 done by opening valve 28 for a time and then closing said valve. 40

When the deodorization of the oil charged into vessel 3 has been completed it is withdrawn from the vessel and discharged through pipe 23 to a suitable receptacle not shown. This may be done by setting valve 10 for flow of oil from 45 vessel 3 and pipe 11 through pipe 5 to valve 8, by setting valve 8 for flow of oil from pipe 5 to pipe 9 with pipe 6 cut off by valve 8, by setting valve 24 for flow of oil from pipe 9 to pipe 23 with pipe 22 cut off by valve 24, and starting 50 into operation the rotary oil pump 25 and continuing its operation until the treated oil is withdrawn.

Instead of originally charging oil from tank 1 into vessel 3 by the aid of the steam nozzle 19, 55 as above described, pump 25 may be used for this purpose instead of nozzle 19, if desired. For this purpose the initial charging would be effected by setting valves 7 and 8 to open the tank 1 to pipe 9 via pipes 4 and 6 and shut off pipe 5 from pipes 6 and 9, by setting valve 24 to open pipe 22 to pipe 9 and cut off pipe 23 from pipes 9 and 22, by setting valve 16 to open pipe 17 to the lower section of pipe 12 and shut off the upper section of pipe 12 from pipe 17 and the lower section of 60 pipe 12, and then operating pump 25 until the charging is completed.

During the use of the apparatus a partial vacuum or sub-atmospheric pressure is maintained in the upper parts of the vessels 3 and 3^a and 70 casing 14 of the heating device 2 by suction through outlets 30, 30^a and 29 resultant from action of a vacuum pump (not shown) which is connected with said outlets, as hereinbefore described. Steam, water vapor, and volatile prod-

ucts of the oil released by the heat and steam treatments described, are withdrawn through said outlets. Preferably the amount of oil charged into each vessel 3 or 3^a is such that the oil level in the vessel is below the discharge ends of pipes 17 and 40 leading into vessel 3 and the corresponding ends of the corresponding pipes 17^a and 40^a leading into vessel 3^a, so that vapor, gases and volatile products of all kinds in oil 5 discharged through said pipes are readily, and largely completely, released in the upper parts 10 of the vessels before the discharged oil reaches the body of oil in the vessel.

The jet of superheated steam discharged upwardly in upstanding pipe 12 by nozzle 19 in charging vessel 3, in circulating oil from and back to vessel 3 through heating device 2, and in circulating oil from the bottom of vessel 3 back into the upper part of vessel 3, is highly advantageous 15 in that the steam helps to heat the oil during both the charging operation and the circulation of the oil through the heating device 2 and also, and particularly, in that the steam jet and pipe 12 provide means for exerting a scrubbing effect or action on the oil which is highly effective in releasing volatile products from the oil to deodorize the oil, said products being discharged into a partial vacuum for prompt withdrawal of said products.

30 From the foregoing description of the deodorization of vegetable oil by use of vessel 3, it will be obvious that a like deodorizing treatment may be given by use of vessel 3^a and that the apparatus provides for carrying on two like processes 35 of deodorization in different or overlapping stages of completion. For example, it will be obvious that, when the process above described and using vessel 3 has been carried to the point at which heater 2 is cut out and no longer used, a like 40 process using vessel 3^a may be started. It is thus possible to use heating device 2 more or less continuously and to have two batches of oil in different stages of treatment at the same time. As the second vessel, and the various pipes, valves, 45 steam discharge devices, and the rotary pump used therewith are designated by numerals similar except for the exponent "a" employed to designate like parts described in connection with deodorizing oil in vessel 3, particular description of 50 the use of the apparatus in carrying out the same process to deodorize oil in vessel 3^a is unnecessary.

The described arrangement of parts also permits of ready steam cleaning of the apparatus.

55 The heating device 2 not only acts to heat the oil, but also to release some volatile products therefrom into casing 14 of the heating device for immediate withdrawal of such released products through outlet 29.

60 What I claim is:

1. An apparatus for deodorizing vegetable oils comprising a deodorizing vessel having a suction outlet at its top for volatile products, an enclosed oil heating device having a suction outlet at the top of its casing for volatile products, and having in its casing an oil heating means, means for discharging oil from the oil heater by gravity into the upper part of the deodorizing vessel above the oil level therein, an upstanding 65 restricted oil conduit exterior of the deodorizing vessel the upper end of said conduit leading into

the oil heater casing to deliver oil and steam over the said heater subject to sub-atmospheric pressure in said casing, means connecting the lower end of said conduit to the bottom of the deodorizing vessel, means connecting said conduit to 5 the upper portion of the deodorizing vessel at a point above the level of the oil therein, means for discharging a steam jet upwardly into said conduit adjacent the lower end of said conduit, and valves for at will causing the oil to flow from 10 the bottom of the deodorizing vessel with steam from said steam jet through said restricted conduit to the heater and thence back to the upper part of the deodorizing vessel, or from the bottom of the deodorizing vessel through the said 15 conduit into the upper part of the deodorizing vessel above the level of the oil therein, whereby small quantities of oil with steam may be passed through the heater under sub-atmospheric pressure for the first deodorizing step, and the oil 20 then delivered into the deodorizing vessel and continuously withdrawn in small quantities from the bottom of the deodorizing vessel and subjected to steam in the said upstanding oil conduit and the steam and oil discharged into the deodorizing vessel above the level of the oil therein for the final deodorizing step to ensure the withdrawal of vapors and steam from the incoming oil 25 before the incoming oil contacts the oil in the lower part of the deodorizing vessel.

30 2. An apparatus for deodorizing vegetable oils comprising a plurality of deodorizing vessels each having a suction outlet at its top for volatile products, an encased oil heating device having a suction outlet at the top of its casing for volatile 35 products and having in its casing an oil heating means, means for discharging oil from the oil heater by gravity into the upper part of any selected one of the deodorizing vessels above the oil level therein, an upstanding restricted oil conduit 40 exterior of each of the deodorizing vessels, the upper end of each of said conduits leading into the oil heater casing to deliver oil over the said heater and subject it to sub-atmospheric pressure in said casing, means connecting the lower end of 45 each of said conduits to the bottom of its cooperating deodorizing vessel, means connecting said conduit to the upper portion of its cooperating deodorizing vessel at a point above the level of the oil therein, means for discharging a steam jet 50 upwardly into each of said conduits adjacent the lower end thereof, and valves for at will causing the oil to flow from the bottom of a selected deodorizing vessel with steam from its said steam jet through its cooperating restricted conduit to 55 the heater and thence back to the upper part of the deodorizing vessel or from the bottom of the deodorizing vessel through the said conduit into the upper part of the same deodorizing vessel above the level of the oil therein whereby oil with 60 steam may be passed from any one of said vessels through the heater under sub-atmospheric pressure and the oil delivered from the heater into a deodorizing vessel and then continuously withdrawn in small quantities from the bottom of 65 the deodorizing vessel and subjected to steam in the said upstanding oil conduit and the steam and oil discharged directly into a deodorizing vessel above the level of the oil therein.

70 JOSEPH STEWART.
